US0D1034718S

(12) **United States Design Patent** (10) Patent No.: **US D1,034,718 S**
(45) Date of Patent: ** Jul. 9, 2024

(54) **MACHINE CENTER**

(71) Applicant: **DN SOLUTIONS CO., LTD.**,
Changwon-si (KR)

(72) Inventors: **Heedong Son**, Changwon-si (KR);
Seungwook Shin, Changwon-si (KR)

(73) Assignee: **DN SOLUTIONS CO., LTD.**,
Changwon-si (KR)

(**) Term: **15 Years**

(21) Appl. No.: **29/797,555**

(22) Filed: **Jul. 1, 2021**

(30) **Foreign Application Priority Data**

Jan. 8, 2021 (KR) 30-2021-0000964

(51) **LOC (14) Cl.** **15-09**

(52) **U.S. Cl.**

(57) **CLAIM**

The ornamental design for a machine center, as shown and described.

DESCRIPTION

FIG. 1 is a perspective view of the machine center, showing the present design.

FIG. 2 is a front view thereof.

FIG. 3 is a rear view thereof.

FIG. 4 is a left side view thereof.

FIG. 5 is a right side view thereof; and,

FIG. 6 is a top view thereof.

The broken lines in the figures depict portions of the machine center that form no part of the claimed design.

1 Claim, 6 Drawing Sheets
